LUG HANGER

Walter Gray, Columbus, Ga.

Application October 19, 1936, Serial No. 106,456

3 Claims. (Cl. 139—154)

This invention relates to a lug hanger for use in connection with looms.

As is well known, lug hangers heretofore and now generally used in connection with the picker staffs of looms are constructed of leather and anchored to the wooden picker staffs by screws extending through the body of the hanger into the staff thereby weakening the latter. The leather type of lug hanger is not durable, as it wears out easily and oftentimes breaks resulting in materially reducing the output of weaving as a discontinuance of the operation of the loom is required to enable the substitution of a new hanger.

This invention aims to not only overcome the objections pointed out as applied to a leather lug hanger, and also to other types of lug hangers secured to wooden picker staffs by screws, but further aims to reduce to a minimum a waste in cloth during weaving caused by breakage of the lug hanger, and to this end the invention resides in providing, in a manner as hereinafter set forth, a lug hanger of metallic material capable of being adjustably anchored to a wooden picker staff without weakening the latter.

Further objects of the invention are to provide, in a manner as hereinafter set forth, a lug hanger of the class referred to which is simple in its construction and arrangement, strong, durable, conveniently anchored to the picker staff, thoroughly efficient in its use and comparatively inexpensive to manufacture.

With the foregoing and other objects in view, the invention consists of the novel construction, combination and arrangement of parts as will be more specifically described and are as illustrated in the accompanying drawing, wherein is shown an embodiment of the invention, but it is to be understood that changes, variations and modifications may be resorted to which fall within the scope of the invention as claimed.

In the drawing:

Figure 1 is a fragmentary view in perspective of a loom showing the adaptation therewith of the picker staff of the latter with a lug hanger in accordance with this invention.

Figure 2 is a fragmentary view in side elevation of a picker staff showing the adaptation therewith of the lug hanger in accordance with this invention.

Figure 3 is a fragmentary view in front elevation of a picker staff showing the adaptation therewith of the lug hanger.

Figure 4 is an exploded view in perspective

of the lug hanger in accordance with this invention, and

Figure 5 is a section on line 5—5, Figure 2.

A lug hanger in accordance with this invention includes a hanger member generally indicated at 1, an abutment generally indicated at 2, a clamping member 3 in the form of a yoke, a pair of washers 4, 5 and a pair of clamping nuts 6, 7.

The members 1, 2 may be formed of any strong, durable material other than leather and preferably the members 1, 2 will be constructed of metal. The yoke member 3 will be formed of metallic material.

A fragmentary portion of a loom is indicated at 8 of which a picker staff 9 of wood forms a part. The coupling lug between the picker staff 9 and an operative part of a loom 8 is indicated at 10.

The hanger member 1 includes a head 11 substantially of semi-ovoidal contour whereby it will gradually decrease in width from its bottom to its top. The member 1 includes a base 12 of a width corresponding to the widest part of the head 11 but of a length materially less than the length of head 11. The lower end or edge of head 11 curves downwardly from the outer to the inner face of the head. The upper end or edge of the base 12 curves upwardly from the outer to the inner face of the base. The member 1 includes a shank 13 of a length greater than that of the head 11 or base 12, but of a width corresponding to the thickness of the staff 9. The head 11 and base 12 are arranged in permanent, parallel, spaced relation on shank 13. The latter at its upper end merges into and centrally of the lower edge of head 11 and at its lower end merges into and centrally of the top edge of base 12. The head 11 between its transverse median and upper end is formed with a pair of spaced, parallel openings 14, 15. The openings are spaced adjacent each side of the vertical median of head 11.

Formed integral with the bottom of the inner face of the head 11 is a pair of inwardly extending parallel spaced tapered lug confining arms 16, 17 of like form. The outer side edges of the arms are flush with the side edges of the head 11. The inner side edges of the arms are spaced outwardly adjacent relative to the side edges of the shank 13. The lower faces of the arms are flush with the bottom edge of head 11. Formed integral with the inner face of the base 12 is a pair of inwardly extending parallel spaced tapered lug confining arms 18, 19 of like

form. The tops of the arms 18, 19 at their outer ends are flush with the top edge of base 12. The outer side edges of the arms 18, 19 are flush with the side edges of the base 12. The lower edges of the arms 18, 19 are spaced above the bottom edge of base 12. The inner side edges of the arms 18, 19 are spaced outwardly relative to the side edges of shank 13. The bottom of base 12 is arranged below the bottom edges of the arms 18, 19. The arms 16, 17 have their inner and outer side edges aligned with the inner and outer side edges of the arms 18, 19.

The abutment member 2 consists of a strip 20 of metal substantially of a length equal to head 11. The width of strip 20 is materially less than that of head 11 but corresponds substantially to the width of the rear edge of the staff 9. The inner face 21 of strip 20 is square. The ends of strip 20 are bevelled. The strip 20 is formed 20 in its outer face with a transverse groove 22. The strip 20 is substantially of segmental contour in cross section.

The member 3 includes a pair of arms 23, 24 respectively formed with peripheral threads 25, 26 at their free end terminal portions. The base 27 of yoke member 3 is rounded.

When the lug hanger is arranged in coactive relation with respect to the picker staff 9 the member 1 is positioned against the front edge 30 28 of the staff 9 and with the shank 13 having its edges flush with the side edges of staff 9. The latter is disposed centrally with respect to the inner faces of head 11 and base 12. The staff 9 is arranged between the arms 16, 17 and between 35 the arms 18, 19. The member 2 is positioned against the rear edge 29 of staff 9 and is disposed centrally with relation to the head 11. The base 27 of member 3 is seated in the groove 22 and the arms 23, 24 of member 3 extend 40 respectively through the openings 14, 15 and project from the outer face of head 11. The washers 4, 5 are mounted on the free end of the arms 23, 24 of member 3 and abut the outer face of head 11. The clamping nuts 6, 7 are 45 then mounted on the arms 23, 24 and screwed home whereby the hanger member 1 and abutment member 2 are clamped to the picker staff 9. As the yoke member 3 is detachably connected to the members 1, 2, the said members 50 may be positioned at any point desired with respect to the length of the staff 9.

The lug 10 of the loom which coacts with the lug hanger, in accordance with this invention, is extended around the shank 13 and staff 9 and is arranged between the arms 16, 17 and arms 18, 19. The arms 16, 17 and 18, 19 arrest the lengthwise movement of lug 10 relative to the staff 9 and the hanger member 1.

The means, forming elements of the lug hanger, for clamping the latter to the picker staff does not weaken the latter and further as the members 1, 2 are constructed of metal breakage of the member 1 during the operation of the loom is reduced to a possible minimum, 65 or in other words, it is free of the objection referred to in connection with the leather type hanger and this statement also applies to the member 2.

The lug confining arms 16, 17 preferably will 70 be of less length and of less thickness than the lug confining arms 18, 19. The bottom edges of the arms 16, 17 will be of curved contour. The top edges of the arms 18, 19 will be of curved contour, but oppositely curved with respect to 75 the curvature of the bottom edges of the arms

16, 17. The curvature of the edges referred to will reduce friction on the lug 10 during the operation of the loom. The top edge of the base 12 forms curved continuations of and coacts with the top edges of the arms 18, 19 to form supporting surfaces for the bottom edges of the lug 10.

What I claim is:—

1. In a lug hanger for use in connection with a picker staff, a one-piece hanger member adapted to be secured to the front edge of said staff, said member including a head, a base, a shank interposed between and merging at one end into and centrally of the lower end of the head and at its other end into and centrally of the upper end of the base, a pair of spaced parallel lug confining arms extending inwardly from the inner face of said head for opposing the sides of said staff and a pair of spaced parallel lug confining arms extending inwardly from the inner face of said base for opposing the sides of said staff, the arms on the head being integral with the lower portion of the inner face of the head, the arms on the base being integral with the upper portion of the inner face of the base, an abutment member for positioning against the inner edge of said staff and having its outer face formed with a transverse groove, said head being formed with spaced openings above the arms carried thereby, and means seated in said groove, extending through said openings and binding against the outer face of the head for clamping the hanger and abutment members to the picker staff.

2. In a lug hanger for use in connection with a picker staff, a one-piece hanger member adapted to be detachably clamped against the front edge of the staff and including a head having its lower edge curved downwardly from the outer face to the inner face of the head, a base having its upper edge curved upwardly from the outer to the inner face thereof, a shank interposed between and merging at its upper end into and centrally of the lower edge of the head and merging at its lower end into and centrally of the upper edge of the base, a pair of inwardly extending spaced parallel upper lug confining arms for opposing the sides of said staff integral with the lower portion of the inner face of said head, the bottom edges of said arms forming flush continuations of the bottom edge of said head, a pair of inwardly extending parallel lower lug confining arms for opposing the sides of said staff integral with the upper portion of the inner face of said base, said lower arms having their top edges forming flush continuations of the upper edge of the base, said head being formed with a pair of spaced openings, an abutment member for positioning against the rear edge of the staff and formed in its outer face with a groove transversely thereof, and means seated in said groove, extending through said openings and binding against the outer face of said head for detachably clamping the hanger and abutment members to the picker staff.

3. In a lug hanger for use in connection with a picker staff, a one-piece hanger member adapted to be detachably clamped to the front edge of said staff and including a head having a lower edge, a base having an upper edge, a shank interposed between and merging at its upper end into and centrally of the lower edge of the head and having its lower edge merging into and centrally of the upper edge of the base, a pair of spaced parallel upper lug confining arms extend-

ing inwardly from the inner face of said head for opposing the sides of said staff and having their bottom edges forming flush continuations of the lower edge of the head, a pair of spaced parallel lower lug confining arms extending inwardly from the inner face of said base for opposing the sides of said staff and having their upper edges forming flush continuations of the upper edge of the base, said upper arms being integral with said head and said lower arms be-

ing integral with said base, an abutment member for positioning against the inner edge of said staff and having its outer face formed with a transverse groove, said head being formed with spaced openings above the upper arms, and means seated in said groove, extending through said openings and binding against the outer face of the head for detachably clamping the hanger and abutment members to the picker staff.
